COLLAR ATTACHMENT

Walter Gehrig, Flint, Mich.

Application April 12, 1937, Serial No. 136,383

11 Claims. (Cl. 24—88)

The present invention relates to attachments for garment collars and garment ornaments such as ties, and is particularly suited to be worn on men's shirts and neck-ties. To simplify the specification I will hereafter describe my invention in combination with a man's shirt and neck-tie only.

The object of the collar and tie attachment is to prevent the collar-tips from curling outwardly and to hold part of the neck-tie in place, thus improving the appearance of the person wearing the shirt and neck-tie.

A collar and tie attachment of similar character is described in my patent application filed

15 August 1, 1936.

I attain the aforesaid objective by a light and continuous pull on the collar tips by the weight of the hereafter described collar and tie attachment in the direction of a point located between 20 and below said collar-tips. A tie holder connected to the collar attachment holds the neck-tie over the lower part of the collar attachment.

In the accompanying drawing wherein for the purpose of illustration are shown preferred embodiments of my invention and wherein like reference characters designate like parts thereof:

Figure 1 is a view of the front part of a detachable shirt-collar and of a neck-tie having my collar and tie attachment attached to the collar 30 tips only.

Figure 2 is a front view of two members of the assembling element and of the lower part of the collar pins; the front point guard and the tie holder have been removed as indicated by the 35 dotted line C—C in Figure 4.

Figure 3 illustrates a tie-pin which can be connected to the collar attachment in place of the tie-clasp 19 shown in Fig. 1.

Figure 4 is a side view of one collar-pin and 40 of the assembling element and illustrates the effect of the location of the center of gravity in the lower portion of the collar attachment on the position of the collar-pins. The collar attachment hangs freely on the collar pin which is 45 attached to a collar-tip shown in section.

Figure 5 is a front view of the upper part of a man's shirt and neck-tie equipped with my collar and tie attachment.

Referring to Figure 1 in the drawing, the number 1 designates a detachable shirt-collar shown with a neck-tie 2. The hereafter described collar attachment can be attached to and detached from the collar tips 3 by means of the collar pins 4. Each collar-pin 4 has a pin-head 5, 55 which forms a stop-shoulder on one terminal

portion thereof. The adjacent terminal portion of the pin body forms a bend 6 (Fig. 4) towards the normal front of the collar attachment and the intermediate portion of the pin-body also forms a bend 7 towards said front side. The 5 other terminal portion of each pin tapers off into a point 8 (Fig. 2) and the portion of the pin-body adjacent to said pointy terminal 8 forms a resilient bend 9 shaped like a hook or part of a coil. The distance across the "mouth" 10 of said hook 9 is smaller than the distance across the center of the "belly" formed by the bend of the pin as shown by the dotted lines and arrows A—A in Fig. 2.

The assembling element for said pins 4 comprises resilient means such as a rubber member 10. Guards for the pointy terminals 8 of the collar-pins are provided in the form of discs 11, 22, which are mounted on each side of the resilient member 10 by means of a pin or rivet 12 (Fig. 1) which also connects a guiding element 13 for a tie-holder to the other parts of the assembling element. The said tie-holder consists of a tie pin having a stop-shoulder or pin head 14 on one terminal portion thereof and tapering off 25 into a point at the other terminal portion 15 (Fig. 3) of the pin. Said pointy terminal portion projects to one side of the adjacent straight part 16 of the pin body, the continuation of which forms bends as shown in Figure 3. The 30 length of the said straight part 16 of the pin-body is about equal to the width of the strip of metal forming the guiding element 13. The tie-pin 14 can be attached to the guiding element 13 by pressing the straight part 16 of the pin-body 35 against the spring pressed mouth 17 (Fig. 4) of the twofold strip of resilient metal. Once the pin-body is past said mouth 17 it is free to slide between the twofold metal strip for a distance which is limited by stops formed by said mouth 40 17 at one side and by the bend 18 of the metal strip at the other side. The point 15 of the tie-pin is approximately flush with the face of the guiding element 13 and so said face acts as a 45 point guard.

The tie-holder 19 shown in Figure 1 is of the clasp-type and can be attached to the guiding element 13 in place of the tie-pin 14 as shown in Figure 1. The clasp type tie holder 19 consists of a strip of resilient metal the terminal portions 50 21 of which are bent over to embrace and clasp the neck-tie. The holder 19 shown in Figure 1 is intended to embrace the inner strand 20 of the neck-tie only in a manner whereby the tie-strand can slide longitudinally therein and thus no tie 55

holder is visible on the front side of the outer strand 2 of the neck-tie.

Of course, a tie holder adapted to clasp both strands of the neck-tie can be substituted for the tie holder 19 shown in Figure 1.

To attach the collar attachment to the collar-tips 3 each collar pin 4 is drawn, point first, and up to the pinhead 5, through the fabric of a collar-tip. The resilient member 10 of the assembling element is then manually pressed into the resilient hook-shaped bend 9 of each collar pin as illustrated in Figure 2. As the belly of the hook is wider than mouth thereof, the resilient action of the rubber member 10 of the assembling element and the spring action of the metal hooks 9 has the tendency to hold the resilient member 10 within the belly of the hook 9, thus securing the pins to the assembling element. The pins 4 however are able to rotate about the center of the assembling element in a plane parallel to the face or front of the wearer of the collar attachment, (which is also the normal face or front side of the collar attachment). The pins 4 can therefore adjust themselves to any distance between collar tips.

The tie-pin 14 is next attached to the neck-tie by pushing said pin, point first and up to the pin head, through both strands 2, 20 of the neck-tie at a point somewhat below the guiding elements 30 and then inserting the straight part 16 of the pin in the guiding element 13. When the wearer of the described attachment stands or sits in normal position then the tie-pin will rest on the lower end or stop 18 of the guiding element 13 and the 35 pin head 14 will carry part of the weight of the neck-tie, thus, to some extent, preventing the tie knot from sliding down.

If the wearer of the collar attachment bends back, then the tie-holder can give to the pull of 40 the neck-tie by moving toward the top of the guiding element 13 until it comes into contact with the upper stop or mouth 17 of the guiding element.

Extra weight is added to the assembling element 45 by the weighty element 22 which also forms one of the point-guards. As can be seen in Figure 4 the front one of the two discs or point-guards 11, 22, is much larger than the one in the back, to bring the center of gravity towards the front 50 side of the lower part of the collar attachment. In Figure 4, one collar pin 4 and the assembling element and tie pin 14 is shown suspending freely from a collar tip 3. The dotted line B-B is drawn through the point of suspension on the upper 55 terminal portion of the pin 4 and through the center of gravity of the lower portion of the collar attachment. The straight part of each pin body between the bends indicated by numerals 6 and 7 are normally resting on the shirt-front if 60 the wearer of the shirt and collar attachment stands in upright position. The said straight part of each pin body is pressed lightly against the shirt front by the weight of the lower portion of the collar attachment and by the pull or pressure 65 caused by the weight of the neck-tie against the assembling element. The said straight part of each pin body has thus a continuous tendency to swing into the inclined position shown in Figure 4. The wearer of the collar attachment can 70 therefore stoop or bend over until the shirt front forms an inclination approximately equal to the inclination of said straight part of the pin body in Figure 4, before the pin body swings away from the shirt front.

75 As many obvious changes are possible in the

shape, size and arrangement of the described elements, without departing from the spirit of my invention, I do not limit myself to the specific construction hereinbefore set forth, except as so limited by the subjoined claims.

Having now described my invention, what I claim is:

1. In an attachment for garment collars, a pin having a stop-shoulder on one terminal portion thereof, a point formed by the other terminal portion of said pin, the pin body forming a bend adjacent to said stop-shoulder and another bend adjacent to said pointy terminal, a point-guard for said pointy terminal adapted to engage the pin by the bend adjacent to the pointy terminal, 15 and resilient means associated with said point-guard to secure the point-guard to the pin.

2. In an attachment for garment collars, a pair of pins, each pin having a stop shoulder on one terminal portion thereof, a point formed by the other terminal portion of said pin, the pin body forming a bend adjacent to said stop-shoulder and another bend adjacent to said pointy terminal, a point-guard for said pointy terminal adapted to engage the pin by the bend adjacent 25 to the pointy terminal by manual pressure, resilient means associated with said point-guard to secure the point-guard to the pin, and the point-guard for one of said pins connected with the 30 point-guard for the other pin.

3. In an attachment for garment-collars, a pair of pins, each pin having a stop-shoulder on one terminal portion thereof, the other terminal portion tapering off into a point, the pin-body forming a bend adjacent to said stop-shoulder, an assembling element adapted to engage said pins by the pin-bodies by means of manual pressure, resilient means associated with said pin-bodies and with said assembling element for securing the pin-bodies to said assembling element, point-guards 40 for the pointy terminals of said pins provided by said assembling element, a tie holder adapted to embrace a neck-tie detachably connected to said 45 assembling element.

4. In an attachment for garment-collars, a 45 pair of collar-pins, each collar-pin having a stop-shoulder on one terminal portion thereof, the other terminal portion tapering off into a point, a bend of the pin-body adjacent to said stop-shoulder, a tie-pin having a pin head on one terminal portion thereof, a point formed by the other terminal portion of the tie pin, an assembling element adapted to engage said pair of collar-pins and the tie-pin by the pin-bodies by means of 50 manual pressure, resilient means associated with said collar-pin bodies and with said assembling element for securing the three pin bodies to said 55 assembling element, point guards for the pointy terminals of said pin-bodies provided by said assembling element.

5. In an attachment for garment-collars, a pair of pins, each pin having a stop-shoulder on one terminal portion thereof, the other terminal portion tapering off into a point, the pin body forming a bend adjacent to said stop-shoulder, 65 an assembling element adapted to engage said pins by the pin-bodies by means of manual pressure, resilient means associated with said pin bodies and with said assembling element for securing the pin-bodies to said assembling element, point guards for the pointy terminals of said pins provided by said assembling element, a tie holder, a guiding element for said tie holder 70 comprised in said assembling element, said tie holder movable in said guiding element but lim- 75

- ited in its movement by stops associated with said guiding element.
6. In an attachment for garment collars and neckties, a necktie-holder including a tie-clasp 5 adapted to embrace and clasp a necktie, a pair of detachable pins pivotally linked to said necktie-holder on the normal lower terminal portion thereof, and means to attach the other terminal portions of the pins to the collar-tips.
- 10 7. In an attachment for garment-collars and neckties, a necktie-holder including a pointy tie-pin having a stop-shoulder and a point-guard, a pair of detachable pins pivotally linked to said necktie-holder on the normal lower portion thereof, and means to attach the other terminal portions of the pins to the collar tips.
- 15 8. In an attachment for garment-collars and neckties, a necktie-holder including a tie-clasp, adapted to embrace and clasp a necktie, a pair 20 of detachable pins, one terminal portion of each pin normally pivotally linked to said necktie-holder by means of an assembling element, and means to attach the other terminal portion of the pins to the collar-tips.
- 25 9. In an attachment for garment collars and neckties, a necktie-holder including a tie-clasp adapted to embrace a necktie, a pointy tie-pin having a stop shoulder and a point guard; a pair 25 of detachable pins, one terminal portion of each pin normally pivotally linked to said necktie-
- holder by means of an assembling element, and means to attach the other terminal portions of the pins to the collar-tips.
10. In an attachment for garment-collars and neckties, a necktie-holder including a tie-clasp 5 adapted to embrace and clasp a necktie, a pair of detachable pins, each pin having a stop-shoulder connected to one terminal portion thereof, the other terminal portion tapering off into a point, the pin-body forming a bend, an assembling element linked to said tie holder and adapted to engage said pins by manual pressure, means associated with said assembling element and with the bends of the pin bodies for pivotally securing the pin-bodies to the assembling element, and 15 point guards for said pointy terminals of the pins comprised in said assembling element.
11. In an attachment for garment-collars and neckties, a necktie-holder including a tie-clasp adapted to embrace a necktie, a pair of detachable pins, each pin having a stop shoulder connected to one terminal portion thereof, the other terminal portion tapering off into a point and forming a hook, an assembling element linked 20 to said tie-holder, means provided by said assembling element and by said hooks to pivotally secure said pins to the assembling element, and point guards for said pointy terminals of the pins provided by said assembling element.
